UNITED STATES PATENT OFFICE

2,574,531

DISCHARGE ASSEMBLY FOR CENTRIFUGAL
SEPARATORS

James Edward Cook, Poughkeepsie, N. Y., assignor
to The De Laval Separator Company, New York,
N. Y., a corporation of New Jersey

Application September 2, 1948, Serial No. 47,358

2 Claims. (Cl. 233—21)

1

This invention relates to centrifuges and particularly to centrifugal separators of the type in which at least one of the separated components of the mixture is maintained out of contact with atmosphere during its passage from the centrifugal bowl to a stationary discharge pipe.

In centrifugal of the so-called "closed" type, as disclosed, for example, in Lindgren Patent No. 2,002,954, the separated components from the chamber of the centrifugal bowl are discharged through separate outlets in the bowl neck which is closely surrounded by flexible and elastic tightening devices or seals. The latter are arranged to accommodate radial vibrations of the neck incident to its rotation, while maintaining separate air-tight communication from each outlet of the neck to a stationary outlet pipe or duct. Centrifuges of this type are in extensive commercial use because of the recognized advantages in thus excluding air from the separated components of certain products.

It is now common practice to provide in one of the stationary discharge pipes of such centrifuges an adjustable yielding resistance to outflow of the separated component, so that by adjusting the resistance, it is possible to regulate the concentration of one of the separated components, for example, the fat content of cream separated from whole milk. A closed centrifuge so equipped is disclosed in Hapgood Patent No. 2,160,140. As there shown, the separated cream or other lighter component discharges through the top of the rotating bowl neck which opens into a stationary receiving chamber in a block removably secured to the centrifuge frame by a nut. The block also assists in holding flexible seals in place around the bowl neck between the cream and skim milk outlets. From the stationary receiving chamber, the cream passes upwardly into a vertical cylinder through a yielding resistance in the form of a spring-loaded disc valve, the loading of which can be adjusted. The valve is guided in its vertical movements by a stem slidable at its lower end in a centrally depressed portion of a valve seat forming the bottom of the cylinder. At its upper end, the stem is connected to a diaphragm mounted in the upper end of the cylinder and serving to counteract the effect on the valve of changes in the back-pressure in the cream discharge line extending laterally from the intermediate portion of the cylinder. The cylinder and the valve seat are removably secured to the underlying block by a second nut.

Separators of the closed type provided with a valved discharge, as described, have substantial

2

operating advantages over prior separators of this type and consequently are used extensively. However, the discharge assembly is somewhat complicated because of the number of parts which heretofore have been regarded as necessary; and the arrangement of these parts materially increases the over-all height of the separator. Moreover, cleaning of the assembly is somewhat complicated by reason of the number and arrangement of the parts and the multiple nuts for holding them together.

The present invention, therefore, has for its primary object an improvement of the above-described discharge assembly for closed centrifuges, whereby the number of parts and the over-all height are reduced, and the parts may be more readily disassembled and cleaned.

A separator made in accordance with the present invention comprises a stationary block seated on the seat surrounding the bowl neck and having in its lower portion a recess forming a receiving chamber for liquid discharged from the bowl through the outlet in its neck. At its upper portion, the block has an integral flange forming a wall of the receiving chamber and defining a valve orifice through which the discharged liquid passes from the receiving chamber into a vertical cylinder or hollow member. The valve orifice in the block is considerably smaller in diameter than the recess forming the receiving chamber, so that the orifice provides a restricted flow path for the liquid. The cylinder contains a disc valve adapted to seat on the block flange to close the orifice. Guiding of the valve is effected entirely within the cylinder, by providing the disc with lateral projections slidably engaging the inner wall of the cylinder. The spaces between these projections allow flow of the liquid up through the cylinder from the valve orifice when the disc valve is unseated. The latter is provided with suitable means for biasing it toward its closed position, thus imposing a yielding resistance to the flow of liquid into the cylinder.

The block is held in assembled relation to the underlying centrifuge frame and the overlying cylinder by means of a fastening element which, however, is spaced from the block. More particularly, the fastening element spans the block and at its lower end is threaded or otherwise releasably connected to the frame. The upper edge of the fastening element has a holding portion overlying an interrupted shoulder on the cylinder, and also has a diametrically opposed locking portion normally overlying the shoulder but adapted, upon rotation of the fastening element, to regis-

ter with the interruption in the shoulder. In the latter position, the cylinder can be tilted without interference from the locking portion, and is then movable laterally to disengage the holding portion and remove the cylinder for cleaning or any other purpose. However, when the fastening element is positioned with its locking element overlying the cylinder shoulder, the cylinder is held firmly against displacement on the block. The block, in turn, holds the seal in place around the bowl neck by downward pressure exerted through the cylinder by the fastening element.

For a better understanding of the invention reference may be had to the accompanying drawing, in which:

Fig. 1 is a vertical sectional view of a centrifuge embodying the invention in a preferred form, and

Fig. 2 is a sectional view on the line 2—2 in Fig. 1.

For illustrative purposes, the invention will be described in connection with a centrifuge of the "air-tight" type commonly used for separating cream from milk. It will be understood, however, that the invention is not limited to centrifuges of this type, or to the separation of cream.

Referring to the drawing, the numeral 10 designates the centrifuge frame in which the centrifugal bowl is mounted for rotation. The bowl may be of any conventional form and therefore is not illustrated, except for the neck 11 having a vertical passage 11a for discharging the cream from the separating chamber in the bowl. The neck 11 is closely surrounded by two flexible seals 12 and 13 of annular form. A spacing member 14 is interposed between the seals and has radial passages 14a through which any leakage between the bowl neck and the seals is led outwardly to an annular clearance space in the upper part of the frame and then discharged through an opening in the frame wall. The central part 12a of the lower seal extends downwardly along the bowl neck and through a central opening 10a in a horizontal internal flange 10b on the frame. At its outer portion, the lower seal 12 is clamped between the flange 10b and the spacer 14. The central portion 13a of the upper seal extends upwardly along the bowl neck, while the outer portion of this seal is seated on top of the spacer 14. At their intermediate portions, the seals are considerably thinner than their inner and outer portions, as shown at 12b and 13b, respectively. By virtue of the relatively thin intermediate portions 12b and 13b, the seals are better adapted to accommodate lateral movements of their inner portions incident to radial vibrations of the neck 11 during rotation of the bowl.

A block 16 clamps the outer portion of the upper seal 13 against the spacer 14. The block 16 is located in a recess 16c in the top of the frame and forms a closure for the latter. Downward movement of the block into the recess 16c, against the seal 13, is limited by a shoulder 16a engageable with the top of the frame. At its lower portion, the block is provided with a central recess 16b forming a receiving chamber for the cream discharged through the neck passage 11a. The outer wall of chamber 16b surrounds the outlet end of neck 11 and the upper or inner portion of seal 13. The diameter of recess 16b is approximately the maximum diameter of the thin portions 12b and 13b of the seals, so that a substantial clearance space is provided between the

upper seal portion 13a and the side wall of the recess 16b.

At its upper portion, the block 16 has an integral, horizontal internal flange 16c forming the upper wall of recess 16b and defining a central valve orifice 17 directly overlying the outlet end of neck 11. The orifice 17 affords communication between the chamber or recess 16b and the interior of a hollow member 18 in the form of a vertical cylinder. The cylinder 18 is seated at its lower end on top of the block where it is held against lateral displacement by a rim 16d integral with the block. The cylinder 18 has a laterally extending duct 19 through which cream entering the cylinder may be discharged to a suitable pipe line connected to the duct.

The flow of cream through the orifice 17 is controlled by a disc valve 20 adapted to seat on top of flange 16c around the orifice so as to close it. As shown particularly in Fig. 2, the disc 20 is of polygonal shape, the corners forming projections 20a engaging the inner wall of the cylinder. In this way, the projections 20a serve to guide the disc valve in its vertical movement, by sliding along the inner wall of the cylinder, while the spaces between the projections constitute passages through which the cream can flow upwardly into the cylinder when the disc valve is unseated. In its lower face, the disc valve is formed with a central recess 20b of somewhat greater diameter than the orifice 17 and having rounded edges.

A stem 21, which may be integral with the disc valve 20, extends upwardly through the cylinder 18 and is connected at its upper end to a flexible diaphragm 22. At its outer edge, the diaphragm 22 is clamped between the upper part of cylinder 18 and a housing 23, by means of a nut 24. A compression spring 25 in the housing 23 engages a pin 26 slidable in a central opening in a horizontal partition 23a in the housing. The pin 26 serves to transmit the downward thrust of spring 25 to the upper end of stem 21, so that the valve 20 imposes a yielding resistance to the flow of cream through orifice 17. The compression of spring 25 may be adjustable by any suitable means (not shown) to vary the resistance imposed by the valve.

The cylinder 18 and the block 16 are held in assembled relation on the centrifuge frame by means of a fastening element 27 which, however, does not engage the block. At its lower end, the fastener 27 is threaded to the upper portion of frame 10, as shown at 27a. From the threaded portion 27a, the fastener extends upwardly and inwardly so as to span the block 16, the upper edge of the fastener engaging the lower portion of the cylinder. At its upper edge, the fastener has a holding portion 27b engaging the top of a shoulder 18a on the cylinder, the holding portion 27b extending circumferentially around the cylinder over somewhat less than 180°. Diametrically opposite the holding portion 27b, the upper edge of the fastener has a locking portion 27c adapted to engage the top of shoulder 18a. The shoulder 18a is formed with an interruption 18b forming a slot somewhat wider than the locking portion 27c. The fastener 27 may be provided on its periphery with spaced projections 27d to facilitate rotation of the fastener, as will be described in greater detail presently.

The operation of the improved centrifuge is as follows: The cream discharging through neck 11 into the receiving chamber 16b completely fills the chamber and acts to press the upper seal 13 against the spacer 14 and also against the bowl

neck, thereby making the seal more effective to prevent leakage. The pressure of the cream in chamber 16b is also exerted against the lower face of valve 20 through the valve orifice 17. When this pressure is sufficient to overcome the downward force on the valve, the latter is moved upwardly from its seat on the flange 16c. As a result, the cream flows upwardly through orifice 17 and against the bottom of recess 20b, the cream then flowing outwardly between the flange 16c and the outer portion of the valve, and then upwardly into the cylinder through the spaces between the projections 20a. Because of the rounded edge of the recess 20b, a gradual reduction of pressure and velocity is effected, which is beneficial in avoiding impacts of the cream tending to break up the fat clusters and reduce the viscosity of the cream. It will be understood that the greater the pressure of the spring 25, the greater the resistance to flow of cream and the more concentrated the cream. Also, any increase in the back pressure in the discharge line from duct 19 will cause an increased upward thrust on diaphragm 22, whereby the effect on disc valve 20 will be counteracted; and conversely, any decrease in the back pressure will reduce the pressure of the cream exerted upwardly against diaphragm 22. Consequently, the flow resistance imposed upon the cream by valve 20 is maintained substantially constant, except for such desired changes as may be brought about by manual adjustment of the compression of spring 25. Thus, the concentration of the cream discharging through duct 19 will be maintained substantially constant at all times for any given adjustment of spring 25, regardless of variations in the feed rate to the bowl or other factors tending to influence the concentration of the cream.

When it is desired to remove the cylinder 18, as for cleaning purposes, housing 23 is first removed by unscrewing nut 24, and any pipe connections are unscrewed from duct 19. The fastener 27 is then unscrewed from the frame 10 at 27a, and the cylinder and the fastener 27 are lifted from the frame. In order to completely separate the cylinder 18 from the fastener 27, the fastener is rotated about the cylinder until locking portion 27c is aligned with the shoulder interruption 18b, as shown in Fig. 2. The cylinder is then tilted so as to raise the side having slot 18b, the opposite side being retained in the holding portion 27b of the fastener. When the cylinder is thus tilted sufficiently to raise its lower end above the level of the locking portion 27c, it may be moved laterally to disengage shoulder 18a from beneath the holding portion 27b, so that the cylinder can be withdrawn from the fastener. It will be understood that when the cylinder is in position on the block, and the fastener 27 is entirely screwed down at threaded portion 27a, the extent of the circumferential holding portion 27b is sufficient to hold the cylinder securely on the block regardless of whether locking portion 27c is in or out of alignment with slot 18b. In order to obtain access to the seals 12 and 13, the cylinder and fastener are removed from the frame as above described, whereupon block 16 may be lifted from recess 10c in the frame.

It will be evident that since block 16 is not engaged by any fastening element, it is free to center itself with respect to the frame and the cylinder 18, to the extent permitted by the tolerances in the fits between the block and the frame and cylinder, respectively. Also, by providing the block itself with the valve orifice 17 in the plane

of flange 16c, the over-all height of the apparatus is considerably reduced. Additionally, the guide means 20a for the valve, being located entirely within the cylinder 18, enable a further reduction in the over-all height. By virtue of the described arrangement of the block and fastener 27, which encloses the block, the apparatus can be readily assembled and completely disassembled.

I claim:

1. In a closed centrifuge having a frame, a centrifugal bowl neck rotatable in the frame and affording outlet at its upper end for a centrifugally separated component, a stationary hollow member communicating with said outlet through a valved orifice and having a discharge passage for said component, and a flexible seal surrounding the neck and secured to the frame to provide air-tight communication between said outlet and orifice, the improvement which comprises a block seated on the seal to hold the same in position around the neck, the block having in its lower face a recess forming a receiving chamber for the component passing through said outlet, a valve seat between said chamber and hollow member and forming said orifice, a valve in said hollow member coacting with the seat to impose a yielding resistance to flow through the orifice between said outlet and said discharge passage, and a fastening element surrounding but spaced from the block and removably secured at one end to the frame and engaged at its other end with the hollow member to hold said member, block and seal in assembled relation on the frame, said hollow member having an interrupted shoulder, and the fastening element having an interrupted edge portion overlying said shoulder, the hollow member and fastening element being rotatable relatively to permit withdrawal of the shoulder through the interruptions in said edge portion.
2. In a closed centrifuge having a frame, a centrifugal bowl neck rotatable in the frame and affording outlet at its upper end for a centrifugally separated component, a stationary hollow member communicating with said rotating outlet through a valved orifice and having a discharge passage for said component, and a flexible seal surrounding the neck and secured to the frame to provide air-tight communication between said outlet and orifice, the improvement which comprises a block seated on the seal to hold the same in position around the neck, the block having a recess in its lower portion forming a receiving chamber surrounding said outlet and adapted to receive the component passing therethrough, the walls of said receiving chamber extending inwardly above said outlet to form a top opening substantially smaller than the open bottom of the chamber and forming said orifice, a disc valve in said hollow member adapted to seat on the block to close the orifice and imposing a yielding resistance to flow between the rotating outlet and the stationary discharge passage, guide means on the disc valve engageable with and vertically reciprocable on the inner wall of said hollow member to center the valve relative to the orifice, and a releasable fastening element spanning the block and threaded at its lower end on the frame, said hollow member having an interrupted shoulder underlying the upper edge of the fastening element, said upper edge having interruptions separating a holding portion of the edge from a diametrically opposed locking portion, whereby upon rotation of the fastening element to align

said locking portion with the shoulder interruption, the hollow member can be tilted to enable its shoulder to be withdrawn laterally from beneath said holding portion.
